UNITED STATES PATENT OFFICE.

HERBERT C. WIRT, OF BOSTON, MASSACHUSETTS, ASSIGNOR OF ONE-HALF
TO JAMES L. KIMBALL, OF SAME PLACE.

DETACHABLE CEILING BLOCK OR BRACKET FOR ELECTRIC LAMPS.

SPECIFICATION forming part of Letters Patent No. 446,826, dated February 17, 1891.

Application filed October 29, 1889. Serial No. 328,549. (No model.)

To all whom it may concern:

Be it known that I, HERBERT C. WIRT, of Boston, county of Suffolk, State of Massachusetts, have invented an Improvement in Detachable Ceiling Blocks or Brackets for Electric-Lamp Fixtures, of which the following description, in connection with the accompanying drawings, is a specification, like letters on the drawings representing like parts.

This invention relates to electric cut-outs of that class in which a cap or rosette is detachably secured to a base, and has for its object to effectively combine with the said cap or rosette a bracket, preferably a hollow rod, to which one or more incandescent lamps may be secured.

The particular features of my invention will be pointed out in the claim at the end of this specification.

Figure 1 in section and elevation represents a cut-out having suspended from it a bracket to which an incandescent lamp is attached; Fig. 2, a top or plan view of the cap or rosette removed, and Fig. 3 a detail to be referred to.

The base *a*, of wood or other insulating material, provided, as herein shown, with contact-arms *a'*, having binding-screws *a²*, and the cap or rosette *a³*, having contact-arms *a⁴*, extended, as herein shown, outside of or beyond the cap, to be electrically connected to the contact-arms *a'* by the screws *a⁵* may be substantially such as shown and described in United States Patent No. 407,077, dated July 16, 1889, granted to myself and James L. Kimball.

In accordance with this present invention the cap or rosette has secured to it a bracket, preferably a hollow brass or other metallic rod *b*, having attached to it an electric incandescent lamp *b'* of any usual or well-known construction. The bracket *b* and its attached lamp may be designed to hang suspended from the cap or rosette so as to swing in a circle, and to effect this result the cap or rosette is provided with an enlarged hole or opening *b²*, through which the end of the bracket *b* is extended up into the cap or rosette, where it is provided with a ball or rounded collar *b³*, provided at one side with a projection (shown as a screw) *b⁴*, which extends into a slot or groove *b⁵* in the cap or rosette, the said ball or collar being herein

shown as screwed upon the said bracket. The cap or rosette *a³* around the opening *b²* is provided with a rounded edge or bead, as at *b⁶*, upon which the ball or collar *b³* rests. The cap or rosette is also provided with an annular ledge *c*, upon which is secured a plate *c'*, preferably of insulating material, to which are secured the contact-arms *c⁴* and contact-plates *c⁵ c⁶*, to which are secured the branch wires *c⁵ c⁶*, connected to the electrodes of the lamp. The collar or ball *b³*, co-operating with the rounded edge of the rosette, forms practically a universal joint, whereby the electric lamp may be turned to occupy various positions from a vertical, as occasion may require.

By securing the bracket to the cap or rosette of a cut-out, as described, not only is a stronger support afforded for the lamp, but one cap or rosette having but a single lamp attached to its bracket may readily be removed and another cap or rosette with a bracket having two or any other number of lamps may readily be secured to the base *a*. Thus it will be seen that for all practical purposes the bracket is rigidly secured to the cap or rosette.

I prefer to employ a cut-out constructed as above described, having the contact-arms extended outside the cap; but I do not desire to limit myself in this respect, as the bracket *b* may be combined with a rosette having its contact-arms on the inside.

I claim—

The combination, with a base and a cap or rosette detachably secured thereto and provided with an opening *b²*, of a bracket *b*, extended up into said opening and provided with a ball or collar *b³*, an incandescent lamp secured to the opposite end of the bracket, an insulated support *c'* within the cap above the opening *b²* and provided with terminals, and branch wires connected to the lamps and extended through the bracket and secured to said terminals, substantially as described.

In testimony whereof I have signed my name to this specification in the presence of two subscribing witnesses.

HERBERT C. WIRT.
